UNITED STATES PATENT OFFICE.

ELMER R. POPE, OF HAMILTON, MASSACHUSETTS, ASSIGNOR TO UNITED SHOE MANUFACTURING CORPORATION, OF PATERSON, NEW JERSEY, A CORPORATION OF NEW JERSEY.

FASTENING CONDUCTING MECHANISM.

Application filed March 13, 1926. Serial No. 94,524.

This invention relates to mechanism for conducting such fastenings as nails in their course from a source of supply to the mechanism at which they are to be utilized, this delivery of the fastenings being in groups or loads which are to be inserted according to a predetermined design. The attachment of heels to shoes calls for the employment of a mechanism of this character. Since the inserting or heelng design varies with changes in heel sizes, it is necessary to correspondingly alter the conducting mechanism. Objects of my invention are to furnish a mechanism which will, in unitary form and as a part of the machine which it is to serve, give the desired nail or fastening-delivering arrangements for all the designs upon which the machine is to operate, this being effected by simple, easily adjusted means compactly arranged. In the attainment of these objects, I combine with means through which the fastenings are delivered from a source, a plurality of groups of conduits movable in a novel manner to bring any one of the groups into co-operation with such delivering means. At one extremity, the openings of these groups of conduits are arranged in accordance with different fastening-inserting designs, while at the opposite extremity the openings of the conduits occupy a mean position; that is, they may be substantially midway between the extremes employed for the largest and smallest of the objects to be attached. As herein illustrated, these conduits, which may be flexible tubes, are in sections, certain of which receive the fastenings in the definite relation in which they are delivered from the source, as in a row, and terminate in different positions, which may or may not be the mean previously mentioned. Other sections, preferably arranged in groups, continue those first mentioned and terminate in accordance with a fastening-inserting design or designs. In such an organization, the groups of tubes or tube-sections which furnish the different designs should be movable relatively to those delivering to them. The arrangement which I prefer for these, and which may be applicable to other purposes than the present, involves movement of the tubes about an axis lying within each of the groups. In this way, the space occupied by the mechanism may be minimized. In the present embodiment of the invention, a

tube common to all the groups provides an axis about which rotates a turret carrying all the tube-groups.

In the accompanying drawing, which discloses a particular form of the invention, 60

Fig. 1 is a top plan view of my improved conducting mechanism;

Fig. 2 is a vertical section therethrough on the line II—II of Fig. 1, with certain parts of a heel-attaching machine and nail-loading mechanism included; 65

Fig. 3 is a partial section taken at right angles to Fig. 2; and

Fig. 4 is a top plan view of the lower disk of the turret. 70

While it is by no means limited to such use, I have chosen to show this conducting mechanism associated with a heelng machine supplied with the attaching nails from a block-loader, this being, for example, as 75 appears in United States Patent No. 1,325,751, Pope, December 23, 1919. Of this machine I have illustrated only a portion of the frame 10 and the block 32, in the openings 33 of which the nails to be driven by 80 the machine are carried, and are delivered load by load through openings 40 in a plate 28. These openings extend in a row transversely of said plate, and register with the upper ends of conduits 48, which may be in 85 the form of flexible tubes carried in openings in a frame or holder 94 mounted at the under side of the plate 28. The lower extremities of the tubes 48 enter openings 96 in a foot-plate 98, this foot-plate being preferably 90 circular and furnishing the bottom of the holder. The arrangement of these openings 96 will later be described. Upon the fixed section 98 of the foot-plate is supported a 95 movable section 100, which carries a plurality of groups of tubes or conduit-sections adapted to continue the fixed sections 48. One of the tubes 48 terminates at its lower end in an opening at the center of the foot-plate, in which is secured a tube 102 depending below said foot-plate. About this tube 102 the plate-section 100 is rotatable, being in the form of a turret made up of an upper disk 104 and a lower disk 106 suitably spaced and held in constant angular relation to each 100 other. The lower disk 106 is pierced by a plurality of groups of openings 108, the openings of each group being equal in number to the nails to be employed in attaching a heel, and each group being differently ar- 110

ranged, corresponding to the various nailing designs required for a run of sizes of heels to be attached by the machine to be supplied. The relation between these groups of design-openings will depend upon the number which are to be employed, as well as the particular arrangement of each; but generally it may be said that they occupy overlapping sectors of the disk 106 with the opening corresponding to the nail which is to secure the rear of a heel to be attached located in the tube 102. Consequently, this tube is common to all the groups of design-openings, and furnishes an axis about which they rotate by virtue of the turret movement. The rear heel-nail, it should be remembered, occupies the same position for all sizes. The groups of openings 108 are joined by conduits or tube-sections 110 to groups of openings 112 in the top disk 104. Like the lower groups of openings, the upper share the tube 102 in common. The remainder of the openings of all groups are identical in arrangement with the foot-plate-openings 96, and in the rotation of the turret 100 may be selectively brought into registration therewith. The positions occupied by the openings 96 and 112 in each group correspond substantially to a mean between the extremes of the largest and smallest of the groups of openings 108. By the utilization of such a relation, the tubes 110 leading to all the groups of lower disk-openings may be kept sufficiently straight to avoid interference with the passage of nails through them. At the same time, a moderate curvature is obtained for the tube-sections 48 leading to the straight row of plate-openings 40. The forms assumed by the groups of openings 108 and the relation of these groups to each other are indicated in Fig. 4 of the drawings, where two adjacent groups are outlined by dot and dot-and-dash lines, respectively. In Fig. 1 appears the outline, in dash lines, of a single group of openings 112 or of the openings 96. Selective registration of the groups of openings 112 in the turret with the group 96 in the foot-plate is permitted by a spring-actuated latch 114, mounted upon the plate 50 and arranged to engage any one of a series of depressions 116 formed about the periphery of the disk 104. In using the mechanism, the operator, having determined what nailing design he wishes to employ for the heels to be attached, releases, if necessary, the turret 100 from the latch 114, and rotates the former until the group of openings 112 connected with the desired design-openings 108 is brought into registration with the foot-plate-openings 96. These settings may be indicated by designations upon the periphery of the turret adjacent to the depressions 116. When thus selected, the turret is secured by the latch. Now, upon the delivery of nails from the block 32, the loads

pass one by one through the tube-sections 48 and aligned chosen group of sections 110, and fall through the disk-openings 108 into the receiving openings of a loader-block 118 carried by a movable loader-arm 120 upon the frame of the heeling machine. By this loader-block they may be transferred to the nailing mechanism in the usual manner. It will be observed that, without removal or replacement of a portion of the apparatus, but, as a unitary construction therein occupying but little space, this mechanism permits the supply of nails from the delivering mechanism for utilization in a considerable number of different designs, as a result of simple changes effected readily and accurately.

Having described my invention, what I claim as new and desire to secure by Letters Patent of the United States is:

1. In a fastening-conducting mechanism, fastening-delivering means, and a plurality of groups of conduits movable about an axis lying within the groups to bring any one of said groups into co-operation with the delivering means, the openings at one extremity of said groups of conduits being arranged in accordance with different fastening-inserting designs, while the openings at the opposite extremity of the conduits are arranged in a mean position between such different designs.

2. In a fastening-conducting mechanism, means arranged to deliver fastenings in definite relative positions, conduit-sections receiving fastenings from the delivering means and terminating in an arrangement differing therefrom, and groups of conduit-sections movable about one of the sections, any one of which groups may be caused to extend the sections first mentioned.

3. In a fastening-conducting mechanism, means arranged to deliver fastenings in definite relative positions, conduit-sections receiving fastenings from the delivering means and terminating in an arrangement differing therefrom, groups of conduit-sections each terminating in a fastening-inserting design different from the associated groups and any one of which groups may be caused to extend the sections first mentioned, and a mounting for all the conduit-sections upon which they are constantly carried.

4. In a fastening-conducting mechanism, means arranged to deliver fastenings in definite relative positions, conduit-sections receiving fastenings from the delivering means and terminating in an arrangement differing therefrom, and groups of conduit-sections rotatable about one of the sections, each group terminating in a fastening-inserting design different from the associated groups and any one of which groups may be caused to extend the sections first mentioned.

5. In a nail-conducting mechanism, nail-

delivering means, nail-tubes leading therefrom, and a foot-plate in which the tubes terminate, said foot-plate having a fixed section and a movable section through which the delivered nails pass.

6. In a nail-conducting mechanism, nail-delivering means, nail-tubes leading therefrom, and a foot-plate provided with openings in which the tubes terminate in fixed 10 relation, said foot-plate including a section having groups of tubes, each group being movable into registration at one extremity with the fixed tubes and at the opposite extremity being arranged in accordance with 15 different nailing designs.

7. In a nail-loading mechanism, a delivering member having openings arranged in a row, flexible tubes leading from the openings, each tube including a plurality of sections relatively movable independently of each other, and a holder upon which the plural tube-sections are mounted together.

8. In a nail-loading mechanism, a delivering member having openings arranged in a 25 row, a frame mounted below the delivery-openings, and flexible tubes leading from the openings, each tube including a plurality of sections relatively movable upon the frame independently of each other, the terminal sections being arranged in a plurality 30 of groups.

9. In a nail-loading mechanism, a nail-block having rows of nail-holding openings, a member having openings corresponding to 35 a row of block-openings and with which said rows may be successively alined, and tubes leading from the openings, each tube including a plurality of sections relatively movable independently of each other and with 40 the delivery-ends of each section having a relation to one another different from the rows of openings.

10. A fastening-conducting mechanism comprising fastening-delivering conduits, 45 and a plurality of groups of other conduits to which those first mentioned may deliver, each group being arranged in accordance with a different fastening-inserting design and said groups of conduits being movable 50 about an axis lying within each group.

11. A fastening-conducting mechanism comprising fastening-delivering conduits, and a plurality of groups of other conduits to which those first mentioned may deliver, 55 each group being arranged in accordance with a different fastening-inserting design and said groups of conduits being rotatable

about an axis lying within a conduit included in each group.

12. In a nail-conducting mechanism, a 60 nail-tube-turret comprising groups of tubes in which there is a tube common to a plurality of groups.

13. In a nail-conducting mechanism, a 65 nail-tube-turret comprising groups of tubes in which there is a tube common to a plurality of groups, such common tube furnishing the axis of the turret.

14. In a nail-loading mechanism, delivering tubes, a foot-plate provided with openings to receive the tubes, a tube fixed upon the foot-plate, and a plurality of groups of tubes movable about the fixed tube.

15. In a nail-loading mechanism, delivering 75 tubes, a foot-plate provided with openings to receive the tubes, a tube fixed upon the foot-plate, and a turret rotatable about the fixed tube and having a plurality of groups of tubes, each group terminating in a different nailing design including the fixed tube.

16. A fastening-conducting mechanism comprising fastening-delivering conduits, and a plurality of groups of other conduits including one common to all the groups and to which those first mentioned deliver, each group being arranged at one extremity in accordance with a different fastening-inserting design and at the opposite extremity in a design common to all.

17. In a nail-loading mechanism, delivering 80 tubes, a stationary foot-plate-section provided with openings to receive the tubes, a tube depending from the foot-plate section, spaced plates rotatable about the axis of the tube and having openings differently arranged in said plates, and tubes connecting the openings in the rotatable plates.

18. In a nail-loading mechanism, a nail-block having rows of nail-holding openings, a member having openings corresponding to a row of block-openings and with which said rows of block-openings may be successively alined, tubes leading from the openings, a foot-plate-section in which said tubes terminate, a tube fixed upon the foot-plate-section, and a turret rotatable about the axis of the fixed tube and provided with groups of tubes each including the fixed element and arranged to register with the tubes terminating in the foot-plate.

In testimony whereof I have signed my name to this specification.

ELMER R. POPE.
